ATTORNEY

UNITED STATES PATENT OFFICE.

CHARLES H. MILLER, OF SAN JOSE, CALIFORNIA.

CLOCK.

Application filed August 1, 1925. Serial No. 47,592.

It is one object of my invention to provide a clock that may be rendered operative by insertion in the circuit of any alternating current electric lighting or heating system.

5 It is another object of the invention to provide a clock of the character indicated equipped with a novel form of circuit breaker mechanism whereby positive and accurate operation of the clock mechanism is assured when properly adjusted.

10 It is still another object of the invention to provide a clock of the character indicated so formed and constructed as to be quickly and easily adjusted to correct inaccuracies in operation, and one that consists of few parts, is economical to manufacture, and highly efficient in its practical application.

15 It is also an object to provide a new, simple and highly effective and accurate mechanism for actuating and controlling the clock pendulum.

20 It is also an object to substitute a more economical and simple motion transmission mechanism for the customary three wheel and pinion structure ordinarily used for driving the hour hand arbor, and to utilize the force of gravity for actuating the clock pendulum and through it the said transmission mechanism.

25 30 It is also an object to provide a simple and effective striking mechanism operating in conjunction with the going side of the clock, and actuated through the medium of electric magnets or solenoids arranged in an alternating electric current circuit, and one that may be easily added to or disconnected from the going side of the clock as desired.

35 40 It is still another object of the invention to provide a striking mechanism of the character indicated wherein the movement of the pendulum is utilized to time the strikes as well as to measure off the time intervals between the striking periods and to set the striking mechanism into operation.

45 This application is a continuation in part of my application for patent for improvement in "clocks", filed October 27, 1924, Serial No. 746,202.

50 In the drawing:—

Figure 1 is an elevation of the working mechanism of the clock.

55 Figure 2 is a perspective view of the going side of the clock as distinguished from the striking side, parts being broken away.

Figure 3 is a perspective view of a portion of the striking mechanism.

Figure 4 is a section on line 4—4 of Figure 1.

Figure 5 is a detail section on line 5—5 of Figure 1 drawn in perspective.

Referring more particularly to the drawings, I show at 1 a rear view of a dial plate of a clock having intersecting bars 2 and 3 mounted parallel thereto and spaced a distance therefrom as at 4 (Fig. 2), these bars being arranged at right angles to each other and parallel to the edges of the plate.

At 5 is shown a pendulum suspended from the upper portion of bar 2 by a resilient element 6 as shown, and at 7 is shown a bar adjustably mounted on the lower portion of the pendulum by screws 8, the upper edge of said bar being recessed to form bevel shoulder 9, seat 10, bevel shoulder 11 and seat 12. On the lower portion of the pendulum is also mounted an adjusting mechanism comprising a fixed bar 13 and a sliding bar 14 connected by a threaded rod 15 fitted with an adjusting nut 16. On the upper portion of the pendulum is mounted an adjustable lug 17 carrying a finger 18 formed as shown for the purpose hereinafter described.

At 19 I show a rectangular frame mounted on bar 2 at right angles to dial plate 1. A hand arbor 20 is mounted in frame 19 and bar 2 and carries a spur gear 21 which meshes with a spiral gear 22 on shaft 23 which also carries a crown toothed wheel 24. The shaft 23 is arranged at right angles to arbor 20 and is mounted in a frame 25 arranged at right angles to frame 19 and connected thereto by means of threaded pins 26 fitted with adjusting nuts 27. When mounted as described the free end of finger 18 engages the teeth on the wheel 24. Obviously, the swinging of the pendulum will actuate the wheel 24 and through it the arbor 20, the swing of the pendulum being limited by stop pins 28 in bar 7.

For actuating and controlling the operation of the pendulum I provide the following mechanism.

Inserted between frame 19 and bar 2 and parallel with arbor 20 is a spindle 29 carrying a block 30. A rod 31 extends upwardly from the top of said block and is adapted to engage the end of an adjustable pin 32 in frame 19 for limiting the swing.

ing movement of the block. A second rod 33 extends downwardly from the block to a point below bar 7 and thence inwardly to a point directly beneath said bar, and is provided with a sharp edge at 34. Extending from each side of block 30 is a rod 35-35^a, the said rods being of equal length and carrying movable cores 36-36^a of solenoids 37-37^a mounted on bar 3. Rod 35^a also carries an adjustable weight 38.

A bar 39 is mounted on bar 3 parallel to bar 2 and adjustably connected to bar 2 by means of a threaded rod 40 passing therethrough and engaging adjusting nuts 41 as shown in Fig. 1.

Mounted on bar 39 is a frame 42. A spindle 43 is inserted in bar 39 and frame 42 and carries a switch element 44 having one portion 45 extending downwardly to contact with a terminal 46 on insulator 47 mounted on frame 42, and another portion extending upwardly and provided with a catch 48 on its under side adapted to engage the edge 34 on rod 33. This finger terminates in a flat portion 49 extending at right angles to the first mentioned portion and adapted to engage the parts 9-10-11 on bar 7.

The electrical connections consist of a clasp 50 on spindle 43 connected by wire 51 to a positive contact with frame 42 as at 52. A wire leads from the terminal 46 to a transformer 53 inserted in an alternating electric current system not shown and thence to a rheostat 54. The two solenoids 37-37^a are connected together by wire 55 and thence to the metal of the clock at 56 where the current flows back to switch 44 through wire 51 and to terminal 46 when the finger portion 45 is in contact therewith.

This going side of the clock having been properly constructed and adjusted as described, a weak alternating current is supplied to the electric circuit through the transformer 53.

When the pendulum is at rest the contact points 45-46 are open, but when the pendulum is swung to the left the bar 49 drops from surface 11 and thus makes an electric contact at 46 and charges the solenoids 37-37^a which draw the impulse arm 33 to the right and into a locking engagement with catch 48, thereby breaking the contact of switch 44 with terminal 46 and breaking the electric current.

Having completed its full swing to the left the pendulum now swings to the right, and when the surface 10 of bar 7 raises the arm 49 it unlocks and releases the impulse arm 33, the overbalancing of the rods 35-35^a causing the said rod 33 to swing to the left. In doing so it engages pin 57 on the bottom of the bar 7 and thereby imparts an impulse to the pendulum to the left again, shoulder 11 on bar 7 permitting the finger end 49 to drop and finger end 45 to contact

again with terminal 46 and so permit the flow of an electric current to relock the rod 33 in engagement with switch 44.

In this manner the impulse rod 33 is electrically actuated to break the electrical circuit and gravity actuated to impart an impulse to the pendulum 5, each swing of the pendulum to the left under a new impulse rotating the arbor 20 a predetermined distance through the action of parts 21-22-23-24-17-18.

For the striking portion of the clock I provide the following mechanism.

A supporting frame comprising rods 60-61-62 is secured to bars 2 and 3 as indicated at 63 and 64 and in the relative positions shown.

On rod 61 and at right angles thereto, is mounted a bracket 65 carrying a spindle 66 (Fig. 4) on which are mounted ratchet wheel 67 and strike count wheel 68, the former being provided with suitably spaced teeth 69 and the latter with a suitable number of unequally spaced notches 70. These wheels are revolvably mounted on spindle 66 with a sleeve 71 inserted therebetween and a washer 72 on the outer end of the spindle and held by a screw 73 so that the two wheels may be relatively adjusted and then secured in their proper adjusted positions by screw 73.

For actuating the counting wheels 67 and 68 during the striking operation I provide a spindle 74 mounted in bracket 65 in parallel relation to spindle 66 and carrying a short bar 75 carrying oppositely directed rods 76-76^a having solenoid cores 77-77^a mounted thereon and operating in solenoids 78-78^a carried by plates 79-79^a mounted on bars 60 and 62 respectively. On the outer end of rod 76^a is a balance 80 and on the outer end of rod 76 is a hammer 81 operating against a bell 82. The rod 76 is provided with a stop 83 carried by plate 1, as shown.

At 84 I show a bar adjustably mounted on rod 76 by means of a screw 85, and pivotally mounted on said bar 84 is a loosely swinging overbalanced finger 86^a positioned to engage the teeth 69 in wheel 67.

On bar 61 is mounted an electrical insulator 82 (Figs. 1 and 3) carrying a metallic standard 83 in which is mounted a rotatable spindle 84 in parallel relation to spindle 66. This spindle 84 carries a finger 85 insulated therefrom as at 86 and adapted to engage the notches 70 in wheel 68.

Spindle 84 also carries a resilient electrically conducting arm 87 having a terminal 88 arranged to contact with a terminal 89 on bar 90 mounted on pendulum 5.

The electrical circuit of the striking mechanism comprises an adjustable attachment to the rheostat at 91, a wire 92 connecting the same with arm 87 as at 93, the contact

points 88-89 connecting the arm 87 with the metal frame of the clock, the wire 94 connecting the frame with solenoid 78^a, wire 95 connecting solenoid 78^a with solenoid 78, 5 wire 96 connecting solenoid 78 with the transformer 53, and thence to the rheostat as described.

This circuit is, of course, normally open and the mechanism quiescent. For setting 10 it in motion the following device is employed.

A T shaped bar 97 (Figs. 1 and 5) is shown secured to one side of the outer member of frame 19, and on this is pivoted an arm 15 98 having its outer end formed to rest upon the wheel 67 to prevent racing thereof, and carrying a freely swinging finger 98^a adapted to engage the teeth 69 in wheel 67. The inner end of arm 98 is fitted with a pivoted 20 element 99 adapted to engage a pin 100 on a small wheel 101 mounted on arbor 20. This element 99 is provided with a stop at 25 102 so that it may raise the opposite end of arm 98 when the pin 100 descends upon the end of element 99 but will freely permit the rotation of pin 101 in the opposite direction.

The action of the strike mechanism is as follows, assuming the electric circuit to be broken at 88-89 and the finger 85 dropped 30 into one of the notches 70 in wheel 68, it being hung on standard 83 in such a manner as to drop into these notches by force of gravity.

Assuming the clock is to strike only upon 35 the hour and the arbor 20 has nearly completed its revolution for the hour. The pin 100 engages element 99 and through it raises arm 98 and finger 98^a so that the finger 98^a engages a higher tooth in wheel 67. The 40 moment the pin 100 passes over element 99 and releases arm 98 it forces finger 98^a downwardly and rotates wheel 67 the space of one tooth. Since the two wheels are mounted to rotate together this action rotates 45 wheel 68 and causes finger 85 to ride up out of the notch 70 on to the perimeter of the wheel. This action rotates spindle 84 a distance and throws the contact point 88 a distance to the right so that at each swing of 50 pendulum 5 the contact 88 carried thereby will engage the contact point 89 and close the electrical circuit.

The closing of the electrical circuit operates solenoids 78-78^a and the hammer 81 is 55 thrown forcibly against bell 82^a. When the pendulum 5 swings to the right and the electrical circuit is broken the weight 80 overbalances hammer 81 and throws it back to a striking position. This backward movement 60 of the hammer rod 76 operates finger 86^a to pull wheels 67 and 68 around the spacing of one tooth in wheel 67. The recurrent closing of the electrical circuit at 88-89 repeats the action of the hammer 81 and finger 65 86^a until the finger 85 drops into the next

notch 70 in wheel 68, this action automatically withdrawing the contact 88 from the reach of contact 89 so that the continued swinging of the pendulum will no longer close the circuit. 70

At 103 is mounted a plate on bar 62 and having a lever 104 pivotally mounted thereon at 105 and carrying a pin 106. If it is desired to lock the striking mechanism against operation it is only necessary to 75 swing the lever 104 over in the direction indicated by the arrow whereupon the pin 106 engages the part 87 and withdraws it to a position where the points 88-89 will not contact as the pendulum 5 swings. 80

This striking portion of the clock can be mounted in connection with the going side or not as desired, and is readily adjustable relative thereto. By removing screws 63 and 85 64, all of the striking part but the bar 97 and parts carried thereby may be removed. By removing screws 107 the remaining parts of the striking mechanism comprising bar 97 and parts carried thereby, are readily removed. By this arrangement a standard clock may 90 be equipped with a striking mechanism at any time without alterations.

It may now be seen that I have provided a simple, accurate clock that may be rendered operative by suitable connection with 95 any alternating electric current system through the medium of a transformer, and one that is so operated as to use but a negligible amount of electricity. 100

I claim:—

1. In a clock, a hand arbor, a pendulum, pendulum operated mechanism adapted to rotate said arbor, an electrical circuit having a switch therein, a pivoted arm adapted to engage said switch and open the same, means 105 carried by said pendulum adapted to engage said switch and release said arm whereby to permit the closing of said switch, and mechanism rendered operative by the closing of said switch for moving said arm back into 110 engagement with said switch.

2. In a clock, a hand arbor, a pendulum, pendulum operated mechanism adapted to rotate said arbor, an electrical circuit having a switch therein, a pivoted arm adapted to engage and open said switch, an unbalanced bar mounted on said arm normally urging said arm out of engagement with said switch, and an electromagnetic device arranged in 115 said circuit adapted to actuate said pivoted arm into engagement with said switch.

3. In a clock, a dial plate, a frame mounted on the back thereof, a hand arbor mounted on said frame, a pendulum suspended on said frame, pendulum operated mechanism adapted to rotate said arbor, an electrical circuit, a supporting bar depending from said frame and having one terminal of the electric circuit positioned thereon, a pivoted switch mounted thereon and provided with 125 130

- the other terminal of the electric circuit, an arm pivotally mounted on said frame and adapted to engage one arm of said switch and separate said terminals and adapted to engage said pendulum, releasable means for holding said arm in engagement with said switch, means carried by said pendulum adapted to engage the arm of said switch and release the said arm from engagement therewith and permit the closing of said switch, a weight carried by said arm to overbalance the same whereby to engage and impart an impulse to said pendulum, and means rendered operative by the engagement of said terminals and closing of said electrical circuit for returning said arm into engagement with said switch.
4. In an electrical clock mechanism, a support, circuit controlling means carried by the support, a pendulum, means carried by the pendulum to close the circuit when the pendulum is moved in one direction, magnetic means to break the circuit during the reverse movement of the pendulum, and gravity actuated means adapted to impart movement to the pendulum in a direction to close the circuit.
5. In an electrical clock mechanism, a hand arbor, a pendulum, pendulum operated mechanism adapted to rotate said arbor, an electrical circuit having a normally open switch therein, means carried by the pendulum to effect closing of the switch when the pendulum is moved in one direction, electromagnetic means to effect opening of the switch, and gravity actuated means adapted to impart a reverse movement to the pendulum to close the switch.
6. In an electrical clock mechanism, a hand arbor, a pendulum, pendulum operated mechanism adapted to rotate said arbor, an electrical circuit having a normally open switch therein, means carried by the pendulum to effect closing of the switch when the pendulum is moved in one direction, electromagnetic means to move and latch the switch in open position, cam means carried by the pendulum to release the latch, and gravity actuated means adapted to impart an impulse to the pendulum to move the same in a direction to close the circuit.
7. In an electrical clock mechanism, a hand arbor, a pendulum, pendulum operated mechanism adapted to rotate said arbor, an electrical circuit having a normally open switch therein, means carried by the pendulum having a depression therein to receive a portion of the switch to permit the same to close when the pendulum is moved in one direction, electromagnetic means to move and latch the switch in open position, cam means carried by the pendulum to release the latch, and gravity actuated means adapted to impart an impulse to the pendulum thereby to move the same in a direction to close the circuit.

CHARLES H. MILLER.
